CLAIM

The ornamental design for a pop-up display CD holder, as shown and described.

DESCRIPTION

FIG. 1 is a perspective view of the pop-up display CD holder in unfolded condition showing my new design;

FIG. 2 is a front elevational view thereof;

FIG. 3 is a rear elevational view thereof;

FIG. 4 is a front elevational view thereof in folded condition;

FIG. 5 is a bottom elevational view thereof in folded condition, the top plan view being identical;

FIG. 6 is a side elevational view thereof, looking from the right side of FIG. 4; and,

FIG. 7 is a side elevational view thereof, looking from the left side of FIG. 4.

The dotted lines shown in the drawing represent fold lines.
